UNITED STATES PATENT OFFICE.

ARTHUR O. MALMGREN AND HENRY KLEFFMAN, OF CHICAGO, ILLINOIS.

VENETIAN BLIND.

1,097,812.

Specification of Letters Patent.

Patented May 26, 1914.

Application filed August 5, 1913. Serial No. 783,075.

To all whom it may concern:

Be it known that we, ARTHUR O. MALMGREN and HENRY KLEFFMAN, citizens of the United States, residing at Chicago, in the county of Cook and State of Illinois, have invented certain new and useful Improvements in Venetian Blinds, of which the following is a specification.

This invention relates to that class of window blinds known as Venetian blinds, and its object is to provide novel and improved means for adjusting the blind slats, this object being attained by means of a combination and arrangement of parts to be herein-after described and claimed.

In order that the invention may be better understood, reference is had to the accompanying drawings in which—

Figure 1 is a front elevation of the blind; Fig. 2 is a vertical section on the line 2—2 of Fig. 1; Fig. 3 is a plan view of one end of the top portion of the blind; Fig. 4 is an elevation of one of the blind supporting brackets; Fig. 5 is an elevation of the mechanism for locking the blind slats; Fig. 6 is an elevation showing the locking mechanism in another position; Fig. 7 is an inverted plan view of a fragment of the top slat of the blind showing the means for locking the raising and lowering cord of the blind.

Referring specifically to the drawings, 10 denotes the slats of the blind. Tapes 11 run down on both sides of the blind and are 15 fastened to the longitudinal edges of the slats. The tapes are flexible so that the slats may be gathered and bunched in superposed relation and carried upward, if the blind is to be raised. The slats are held spaced between the tapes by cross tapes 12 extending 20 between the front and rear tapes 11, between which cross tapes the slats are loosely held. The top slat 13 of the blind, as well as the bottom slat 14, are heavier than the 25 remaining slats, and the former has trunnions 15 and 16, respectively, projecting from its ends.

The blind is hung from a stationary rail or other support 17 which is suitably secured to the top of the window casing. The rail carries outstanding brackets 18 and 19, respectively. The bracket 18 has a curved slot 20 in its top edge forming a slot for the trunnion 15, and the bracket 19 has a 55 pivot opening in which the trunnion 16 is journaled. A pivotal support for the top

slat 13 of the blind is thus provided, which is for the purpose of tilting said slat and the remaining slats to allow the passage of more or less air and light. The slats all tilt together by reason of the connections 11 therebetween.

The following means are provided for tilting the slats: Back of the top slat 13, and outstanding from the bracket 19, is a stud 21 on which is pivoted, at one of its ends, a pawl 22 having at its opposite or free end a downturned portion 23 which overhangs the trunnion 16 and acts as a weight and also as a stop against the trunnion. Intermediate 70 the ends of the pawl, the bottom edge thereof has a series of teeth 24 which are adapted to engage a pin 25 projecting from a plate 26 secured to that end of the slat 13 which carries the trunnion 16. The last-mentioned 75 end of the slat 13 is spaced a sufficient distance from the bracket 19 to accommodate the pawl 22 and the parts coöperating therewith. On the side of the pawl, remote from the end of the slat 13, is pivoted at 27, a prop device 28, the free end of which latter is adapted to engage a pin 29 projecting inward from the bracket 19 toward the slat 13.

When the blind slats are in horizontal position the maximum amount of light and air 85 can pass therebetween. In this position of the slats, the pin 25 seats in the foremost one of the teeth 24 and adjacent to the inclined edge 30 formed by the part 23 of the pawl 22. If it is desired to close the slats 90 more or less, a pull on a cord 31 fastened to the top slat 13 tilts the latter downward toward the front, thereby causing the pin 25 to slide downward along the incline 30. It is to be noted that the teeth of the pawl 95 are arranged in a straight line and the incline 30 is perpendicular thereto, these arrangements having the important functions of checking sudden downward movement of the front edge of the slot 13 which might 100 cause the pawl to throw back out of operative position or, by sudden lifting of the pawl, permit the prop to swing so far forward as to lie in front of the pin 29. This causes the pawl to swing upward, whereupon the prop 28 swings downward and its free end engages the pin 29, thereby holding the pawl in elevated position. The prop normally rests against the pin, so that when the pawl is elevated as described, the bottom 110 edge of the prop engages the pin. The cord 31 is now released, whereupon the top slat

tilts downward toward the rear. The trunnions of the top slat are off the center thereof, so that the slat has a normal tendency to tilt rearward. When the last described 5 tilting movement of the top slat takes place, the pin 25 strikes the prop 28 and knocks the same off the pin 29. This releases the pawl 22 and the latter drops down to engage one of the teeth 24 with the pin 25, 10 thereby locking the top slat in the rearwardly inclined position. As hereinbefore pointed out, the other slats assume the same position by reason of the flexible connections 11. To return the slats to horizontal position, it is necessary only to give the cord 31 a pull. The rear end of the top slat then swings upward, the pin 25 riding over the teeth 24. Should the cord be released, backward motion of the top slat will not result 20 as the pin will be held by the last tooth reached. The only way a return movement may be had is by a sudden pull and release of the cord.

By the means herein described the blind 25 slats can be set at any angle to allow the passage of more or less air and light, and they are securely held in adjusted position by the pawl.

The following means are provided for 30 raising and lowering the blind: The two ends 32 and 32^a of a cord are fastened to the bottom slat 14, from which latter they pass upward through vertically aligned apertures in the slats 10. On the under side of the top 35 slat 13 is a guide eye 33 for the end 32 of the cord, from which guide eye the cord passes through guide eyes 34. A guide eye 35 is provided for the end 32^a of the cord from which it passes through the eyes 34 40 with the other portion of the cord. The bight 36 of the cord hangs down in front of the blind, and by pulling thereon, the blind is raised, the bottom slat 14 as it rises gathering and bunching the slats 10 in superposed 45 relation and carrying the same toward the top slat 13. When the cord is released the slats drop down.

In order to hold the blind at any desired 50 height a cord clamp is provided, the same comprising a spring-actuated cam lever 37 mounted on the under side of the top slat 13, opposite a block 38, between which lever and the block the two parts 32 and 32^a of the elevating and lowering cord pass. The 55 cam lever normally grips the cord, and upon swinging the same rearward, the cord is released. To the cam lever is connected a line 39 for swinging the same to release position, said line extending down 60 in front of the blind. The cam lever may be provided with a housing which is shown dotted at 40 in Fig. 7.

The cam lever grips the two cord strands one way only so that there is no resistance when the shade is being raised. The spring 65 of the cam lever causes the latter to press on the cord strands and the only purpose of said lever is to prevent the shade from dropping when the pull cord is released.

We claim:

1. In a Venetian blind, a top slat having trunnions at its ends off the center of said slat, supports for the trunnions, a pin projecting from one end of the top slat, a toothed pawl pivoted to the trunnion support adjacent to the pin, the teeth on said pawl being arranged in a straight line, the teeth of the pawl being adapted to engage the pin, a pivoted prop carried by the pawl, and a pin carried by the aforesaid support 80 and engageable by the prop to hold the pawl elevated, the prop being disengageable from said pin by the first-mentioned pin into the path of which latter the prop extends.

2. In a Venetian blind, a top slat having trunnions at its ends, supports for the trunnions, a pin projecting from one end of the top slat, a toothed pawl pivoted to the trunnion support adjacent to the pin, the teeth on said pawl being arranged in a straight line, the teeth of the pawl being adapted to engage the pin, a pivoted prop carried by the pawl, and a pin carried by the aforesaid support and engageable by the prop to hold the pawl elevated, the prop being disengageable from said pin by the first-mentioned pin into the path of which latter the prop extends.

3. In a Venetian blind, a top slat having trunnions at its ends off the center of said 100 slat, supports for the trunnions, a pin projecting from one end of the top slat, a toothed pawl pivoted to the trunnion support adjacent to the pin, the teeth on said pawl being arranged in a straight line, the teeth of the pawl being adapted to engage the pin, said pawl having an incline 105 over which the pin rides when the top slat is swung in one direction, said incline being arranged perpendicular to the line of teeth, whereby the pawl is elevated, a pivoted prop carried by the pawl, and a pin carried by the aforesaid support and engageable by the prop to hold the pawl elevated, the prop being disengageable from 110 said pin by the first-mentioned pin into the path of which latter the prop extends.

In testimony whereof we affix our signatures in presence of two witnesses.

ARTHUR O. MALMGREN.
HENRY KLEFFMAN.
